UNITED STATES PATENT OFFICE

151,416

DESIGN FOR A SLED

Carl W. Sundberg, Birmingham, Mich., assignor
to Pratt Manufacturing Company, Coldwater,
Mich., a copartnership

Application March 7, 1947, Serial No. 137,443

Term of patent 14 years

(Cl. D34—15)

To all whom it may concern:

Be it known that I, Carl W. Sundberg, a citizen of the United States, residing at Birmingham, Oakland County, Michigan, have invented a new, original, and ornamental Design for a Sled, of which the following is a specification, reference being had to the accompanying drawings, forming a part thereof, wherein:

Fig. 1 is a top view of a sled, showing my design.

Fig. 2 is a side elevation of the sled shown in Fig. 1.

Fig. 3 is a rear elevation of the sled shown in Fig. 1.

Fig. 4 is a front elevation of the sled shown in Fig. 1.

The opposite side of the sled is the same as shown in Fig. 2.

I claim:

The ornamental design for a sled, as shown and described.

CARL W. SUNDBERG.
